RELAY FOR ALTERNATING-CURRENT MOTORS

Alexander J. Lewus, Cicero, Ill.

Application June 16, 1947, Serial No. 754,823

3 Claims. (Cl. 200—87)

1

The present invention relates to an electric current relay apparatus for alternating current induction motors of capacitor or split-phase type, having a starting and running windings.

The principal object of the present invention is the provision of regulating means whereby the ampere turns on relay coil may be regulated mechanically in direct proportion to the corresponding magnetic pull impressed on relay coil.

A still further object of the present invention is the provision of a relay of the character indicated whereby the surge of amperage at the initial stage of motor operation is capable of energizing a solenoid in the relay for connecting the starting winding in the circuit, and whereby the latter winding may be cut off from the circuit as the amperage in the running winding is reduced to a normal operation and as the motor commences to run at a normal speed at full load or due to any current surge or overload impressed on the motor.

A still further object of the present invention is the provision of a relay, whereby, on closing of a switch for supplying electric current to the motor, the starting winding may become automatically connected in a circuit, and which may continue to be so connected until the motor comes up substantially to four-fifths of the normal speed, and when this has taken place the starting winding may automatically become disconnected from the circuit by the operation of the relay, from which point the running winding alone takes up the function of the operation of the motor.

A still further object of the present invention is the provision in the relay of the character indicated of adjustable means for connecting or disconnecting the contacts in the relay, to conform the same to the particular amperage of any given motor.

With the above general objects in view and others that will appear as the invention is better understood, the same consists in the novel construction; combination and arrangement of parts hereinafter more fully described, illustrated in the accompanying drawings and pointed out in the appended claims.

In the drawings forming a part of this application and in which like designating characters refer to corresponding parts throughout the several views;

Fig. 1 is a diagrammatical view of the circuit with which the present relay is connected;

Fig. 2 is a side elevational view of the relay, illustrating the position of parts thereof when

2

relay remains inoperative or at the stage when an electric motor is running;

Fig. 3 is a top elevational view thereof;

Fig. 4 is an end elevational view thereof;

Fig. 5 is a cross-sectional view on line 5—5 of Fig. 2;

Fig. 6 is a cross-sectional view longitudinally of the relay, illustrating the position of parts thereof during the initial stage of operation of an electric motor;

Fig. 7 is a similar view, illustrating the position of parts of the relay when the solenoid thereof is further energized;

Fig. 8 is a similar view, illustrating the position of parts of the relay during the complete operation thereof; and

Fig. 9 is a diagrammatical view of another circuit with which the present relay may be employed.

Referring to the electric circuit, shown in Fig. 1, the same includes motor 10 to which a pair of outside electric wires 11 and 12 lead and connect the same with a source of electric power. Wires 11 and 12 connect with switch 13. Wire 11 connects with starting winding 14. Wire 15, which hereinafter will be referred to as starting line, connects with said starting winding 14 and leads to starting line contact 16. Said starting line 15 may be connected to condenser 17.

Outside wire 12 connects with, or forms coil 18 which encompasses solenoid core 19, and leaves the latter as running line 20, on which running winding 21 is positioned. The opposite end of said running line 20 connects with outside wire 11 intermediately of switch 13 and starting winding 14, at point 22. Running line 20 connects with contact supporting member 23, which supports running line contact 24.

When switch 13 is thrown on the electric circuit is completed through wires 11 and 12, running line 20 and running winding 21, in consequence of which core 19 will become energized to set the relay, which forms the subject-matter of this application, in operation, for the purpose of bringing contact plate 25 towards contacts 16 and 24, and thereby bridging starting line 15 and running line 20.

The initial surge of electric power in the circuit last hereinabove described brings into the circuit starting winding 14 for starting the motor. After the motor has been started, by the consequence of the utilization of electric load by starting winding 14, the amperage in coil 18 has been reduced to an extent to deenergize core 19 in order to release contact plate 25 from its en-

gagement with contacts 16 and 24 for the purpose of eliminating starting winding 14 from the circuit. By that time however running winding 21 has commenced its operation and continues to run the motor.

The above described electric circuit and the relay for automatically bringing the starting winding into the circuit and to automatically cut the same out of the circuit after the running winding has commenced to operate the motor, are well known in the art. The novel features in the relay presently described reside in the construction of the relay and in the adjustable mechanism whereby the armature lever for actuating contact plate 25 may be adjusted to 15 the particular amperage in coil 18 for energizing core 19. This adjustable mechanism, hereinafter described, permits the interchangeable use of a relay in connection with various motors of various horsepower and in connection with 20 electric loads of various amperage.

The relay herein disclosed includes base 26 made of non-conducting material. Affixed by a pair of screws 27 to said base 26 is leg portion 28 of contact supporting member 29, which supports contact 16 above and in a spaced relation with said base 26 and substantially in a central relation therewith. One of said screws 27 constitutes a terminal for starting line 15, by means of which the latter is clamped to the underface of said base 26.

Contact supporting member 23 upwardly extends from leg portion 30, which is affixed to base 26 by a pair of screws 31, one of which forms a terminal for the end of running line 20 which leaves coil 18, while the other of said screws 31 constitutes a terminal for the continuation of said running line 20, which is nearest to running winding 21. The latter screw 31 clamps the end of said continuation of running line 20 to the underface of said base 26, as is clearly seen in Fig. 4. In effect therefore said leg portion 30 is a continuation of running line 20 as the same leaves coil 18.

Contact supporting member 23 extends above said base plate 26, its free upper end, which supports contact 24 being in a spaced relation with a corresponding end of contact supporting member 29, longitudinally of base 26.

Terminal plate 32 is affixed to base 26 by means of a pair of screws 33. One of said screws 33 constitutes a terminal for outside wire 12, by means of which the latter is clamped to the underface of base 26, while the other of said screws 33 constitutes a terminal for the continuation of said wire 12 which leads to coil 18. Thus, in effect said terminal plate 32 is a continuation of wire 12. Coil 18 is in effect a continuation of wire 12 and running line 20.

Longitudinally of base 26, and disposed thereabove, is contact plate 25 provided at each of its ends with contact 34, one disposed below each of contacts 16 and 24.

Positioned longitudinally of base 26 and intermediately of contact supporting members 23 and 29, is a pair of spaced pins 35 which project in an upward direction from said base 26, and which may be provided with screw heads 36 at one of their ends to engage the underface of said base 26. From the free ends of said pins 35 nuts or flanges 37 are insertable thereon for clamping said pins 35 to said base 26 whereby said pins 35 may be maintained in a rigid relation with base 26. Contact plate 25 is provided with a pair of openings 38 wherein said pins 35 are accommo-

dated for permitting sliding of contact plate 25 to or away from contacts 16 and 24, said pins 35 guiding said contact plate 25 in its sliding movement. Coil spring 39 interposed between contact plate 25 and said nuts 37 normally urges said contact plate 25 towards contacts 16 and 24 in order that said contacts may contact with contacts 34 carried by said contact plate 25 for the purpose of bridging the gap between said contacts 16 and 24 so that starting winding 14 and starting line 15 may be brought into the electric circuit when core 19 is energized on closing switch 13 preparatory to the starting of the motor, as is apparent from Fig. 1.

Forming an integral part of the relay is the armature supporting standard 40, provided at its lower end with an integrally formed horizontal leg portion 41 which contacts base 26 and supports coil 18 and core 19. Screw 42 passed through base 26 and said leg portion 41 engages core 19 and maintains coil 18, core 19, standard 40 and leg portion 41 in a mutually rigid relation and in a rigid relation with base 26. Extending from the opposite end of standard 40, and in a direction opposite from that of leg portion 41, is plate 43 which overhangs contact plate 25. Said screw 42 is preferably made of a non-magnetic material.

From the free end of said plate 43 lip 44 extends in a downward direction toward base 26 and is at an incline, away from standard 40. The purpose of said plate 43 and lip 44 will be hereinafter described.

The armature which is attracted by core 19 when the same is energized includes an oblong lever 45, which extends from a wider head 46, having resulting shoulder 47 on each of its sides, which bear against the adjacent face of standard 40 and prevent the longitudinal shifting movement of lever 45 away from standard 40. Said standard 40 above the plane of the upper end of core 19 is provided with a transverse slot 48 of the length substantially corresponding to the width of lever 45, said slot 48 being wider than the thickness of said lever 45 for permitting angular shifting movement of the latter when positioned within said slot 48.

The free end of head 46 is provided with a downwardly depending flange 49, which is at an incline away from standard 40. Affixed to said flange 49 by means of a pair of screws 50 is a tongue 51 made of a non-conducting material. Said head 46 at its end adjacent flange 49 is provided with a rectangular opening 52, which partially extends into said flange 49, for the purpose hereinafter described.

When core 19 is deenergized lever 45 and head 46 remain at an incline, with tongue 51 bearing against contact plate 25 for maintaining the same in a retracted position away from contacts 16 and 24, against the action of coil spring 39. Slot 48 is sufficiently wide for permitting shifting pivotal movement of said lever 45 within standard 40.

The means for normally maintaining lever 45 and head 46 in their shifted position, with tongue 51 bearing against contact plate 25, as seen in Fig. 2, includes screw 53 passed through lip 44 and in a threaded engagement therewith. The outer end of said screw 53 receives adjusting nut 54 in a threaded engagement with said screw 53, with washer 55 interposed between said lip 44 and nut 54. The inner end of said screw 53 is rounded as at 56, imparting to said end a semi-spherical formation. Said semi-spherical end 56 of screw 53 partly enters the inner end of tubular mem-

ber 57, the inner peripheral margin of said inner end of tubular member 57 being suitably rounded in conformity with the arc of said semi-spherical end 56 of screw 53 for providing a seat for said semi-spherical end 56 of screw 53 within said inner end of tubular member 57. By virtue of this arrangement said inner end of tubular member 57 is swivelled upon the inner end of screw 53, permitting said tubular member 53 to make angular shifting motion with respect to said screw 53 in all directions. Said inner end of tubular member is provided with flange 58.

Receivable within the opposite end of said tubular member 57 is shaft 59, the outer end of which is flattened for effecting wing 60, the outer edges of which are outwardly flaring, and the outer transverse edge of which is arcuate. Receivable upon said shaft 59 is washer 61. The outwardly flaring lateral edges of said wing 60 limit the shifting movement of said washer 61 in the direction away from the tubular member 57.

Interposed between said flange 58 and washer 61 is coil spring 62, which is in an encompassing relation with said tubular member 57 and shaft 59.

The transverse arcuate edge of wing 60 is in engagement with the transverse edge in head 46 defined by opening 52. Spring 62, bearing against flange 58 and washer 61, urges shaft 59 away from screw 53 and towards the said edge in head 46, thereby maintaining said wing 60 in engagement with head 46, and exerting pressure upon said head 46 for normally maintaining tongue 51 against contact plate 25 for holding the latter in a retracted position and away from contacts 16 and 24, as is seen in Fig. 2. The aforesaid action of spring 62, shaft 59 and wing 60 upon head 46 and tongue 51 maintains lever 45 in an angularly shifted position and out of engagement with core 19 when the latter is deenergized.

It is further observed that the greatest degree of pressure upon head 46 exerted thereon by coil spring 62, shaft 59 and wing 60 is at the time when said head 46 and lever 45 remain in an angularly shifted position, with contact plate 25 retracted from contacts 16 and 24, as seen in Fig. 2, because in that position the angle defined by said spring 62, shaft 59 and wing 60, on one hand, and said head 46 and lever 45, on the other, is sharper than the angle defined thereby when lever 45 commences to shift into a horizontal position, or parallel with base 23, as seen in Figs. 6, 7 and 8. This, for the reason that said spring 62 in the first of the above named positions tends to exert pressure upon head 46 to a greater degree from transverse direction with relation to head 46, while in the last named position of said spring 62 with relation to head 46 and lever 45 the former tends to assume a position substantially co-extensive with the longitudinal axis of lever 45, and thereby the transverse pressure thereof upon lever 45 tends to diminish and dissipate.

Thus, the initial surge of electric power through coil 18, on closing switch 13, is of sufficient intensity to energize core 19 to a degree to attract lever 45 from a comparative distance and against comparatively greater pressure of spring 62 against head 46 to elevate tongue 51 for bringing contact plate 25 in contact with contacts 16 and 24, than is required when lever 45 approaches core 19, because then the pressure of spring 62 on head 46 diminishes, as was hereinabove described.

The tension of coil spring 62 for varying the pressure thereof upon head 46 and lever 45 is

capable of regulation and adjustment by means of screw 53. When said screw 53 is driven inwardly, on first loosening nut 54, tubular member 57 shifts upon shaft 59 towards washer 61, thereby decreasing the distance between flange 58 and washer 61 and consequently decreasing the space within which said coil spring 62 is longitudinally confined. This operation will of course increase the tensioning action of spring 62 and the degree of pressure thereof upon head 46. Conversely, on driving screw 53 into the opposite direction, the tension of spring 62 and its pressure upon head 46 will be decreased. This regulation of the degree of tension of spring 62 permits the employment of the same relay in connection with electric circuits of various amperages and consequent various degrees of energization of core 19.

Placed on the underside of plate 43 is oblong rigid plate 63 which is in a transverse relation with said plate 43 and by one of its edges is in contact with the adjacent side of standard 40, as seen in Figs. 6, 7 and 8. One end of said plate 63 has an integrally formed and downwardly depending U-shaped bend 64, the free end of which contacts and bears against the adjacent marginal portion of plate 43 and forms a pivot on which said plate may angularly shift. Passed through said plate 43 and the body portion of said plate 63 is pin 65, which is provided at its lower end with an integrally formed knob 66 and with a rivet head 67 at its upper end. Both said plate 43 and plate 63 are provided with registering apertures within which said pin 65 is accommodated for longitudinal shifting movement, the aperture in said plate 63 being sufficiently large so as to permit the unobstructed shifting movement of said plate 63, as will be later apparent. Interposed between knob 66 and the body of plate 63 is coil spring 68, which encompasses the lower end of pin 65. Normally said spring 68 exerts tension against knob 66 for urging plate 63 in contact with plate 43.

In threaded engagement with plate 43 and adjacent the free end of plate 63 is screw 69 having an adjusting nut 70. On loosening nut 70 screw 69 may be driven downwardly against plate 63 for the purpose of deflecting the same from plate 43, as indicated by dotted lines in Fig. 5. The downward shifting of plate 63 tends to compress spring 68 requiring greater force to overcome the tension of said spring 68 in order to shift pin 65 in an upward direction when pressure is exerted upon knob 66.

Knob 66 overhangs the inner end of head 46 and remains in the path of movement thereof as the same shifts to or away from base 23.

On reference to the relative positions of pin 65 and head 46 as illustrated in Figs. 2, 6 and 7 it will be seen that within a range of angular shifting movement of lever 45 illustrated in the said figures pin 65 does not bear against head 46. It is only at the time when lever 45 is in the nearest proximity of core 19 and approaches a horizontal position when said core 19 is energized and lever 45 is attracted thereto, that pin 65 bears against and exerts pressure upon head 46 by virtue of the action of coil spring 68. Thus, when lever 45 is in contact with core 19 pin 65 exerts the greatest pressure upon head 46, said head 46 causing the upward shifting movement of pin 65 and compressing coil spring 68. When the magnetic flux in coil 18 diminishes to a sufficient degree, but notwithstanding the energization of core 19 and consequent contact with lever 45, and in spite of the action of spring 62, shaft

59 and wing 60, pin 65 will be capable of breaking the connection between core 19 and lever 45 for shifting head 46 downwardly. As said head 46 leaves pin 65, spring 62, shaft 59 and wing 60 will continue to shift head 46 downwardly as well as tongue 51, the latter shifting contact plate 25 away from contacts 16 and 24.

From the hereinabove description it will be readily seen that when switch 13 is thrown on, the initial surge of electric current passing through coil 18 is of such great intensity as to be capable of energizing core 19 to a degree whereby core 19 is capable to attract lever 45 and overcome in succession the pressures of springs 62 and 68 as they bear against head 46 through the medium of wing 60 and pin 65, respectively. As head 46 comes in contact with knob 66 and shifts pin 65 upwardly against the tension of coil spring 62, as lever 45 approaches the horizontal position, at that very instant the action of spring 62 on head 46 diminishes, as was hereinabove described. It is noted however that the initial shifting of lever 45 towards core 19, against the tension of spring 62, shifts tongue 51 in an upward direction for permitting contact plate 25 to come in contact with contacts 16 and 24, even before said head 46 has come in contact with knob 66 and before lever 45 has come in contact with core 19. At the time starting winding 14 has completed its function and running winding 21 takes up the function of running the motor, at that very instant the flux in coil 18 diminishes to an extent so as to render the thrust of pin 65 at head 46 capable to break the connection between core 19 and lever 45. When that was done and head 46 comes out of contact with knob 66 spring 62 takes up the continuing function of shifting head 46 downwardly for shifting tongue 51 against contact plate 25 and against the tension of spring 39 for breaking the contact between contacts 16 and 24, with contact plate 25, head 46 and lever 45 eventually coming to a normal inoperative position illustrated in Fig. 2, which is the position when motor 10 is either at rest with switch 13 open or when the same is in a running condition by the action of running winding 21 and with starting winding 14 out of the electric circuit.

From the construction of the relay described it will be seen that the degrees of tension of springs 62 and 68 may be regulated by means of screws 53 and 69, respectively. The regulation and adjustment of the tension of said springs will adopt the relay for employment with various amperages of the electric circuit and consequently with various motor horsepower. When the amperage in the electric circuit is greater the attraction and contact between core 19 and lever 45 will be proportionately greater, and hence in order to break the connection therebetween the degree of tension in springs 62 and 68 must be greater. Hence the mechanism for regulating and adjusting the tension of said springs as was hereinabove described.

If desired the relay may be enclosed within a suitable housing of non-conducting material and then the entire assembly may be affixed within an electric motor. When the relay is used with any given motor as a permanent fixture thereof, the adjustment of tension in springs 62 and 68 should of course be first made in said springs to conform to the particular amperage used in a given motor.

While the circuit shown in Fig. 1 has the relay in series with starting and running windings,

Fig. 9 illustrates another exemplification of a circuit in which relay coil 18 is in series with the running winding only. In that latter figure the outside wire 12 connects with one of the terminals 31 in the terminal plate 30. Connecting with other terminal 31 is the continuation of said wire 12, which leads to and connects with one end of coil 18. Connected with the opposite end of coil 18 is running line 20 having running winding 21, and which connects with the other outside wire 11 at 22. Starting line 15, having starting winding 14 connects at point 22 with said wire 11 and line 20. The opposite end of said starting line 15 connects with terminal plate 28. Otherwise the 10 operation of the relay, although reversed, is identical with that in Fig. 1. When switch 13 is thrown on, the initial surge of current passes through wires 11 and 12, running line 20, running winding 21, terminal plate 30, and coil 18 to energize core 19. Core 19 attracts armature 45 which brings contact plate 25 in contact with contacts 16 and 24. This establishes the circuit through starting winding 14, starting line 15, terminal plate 28, contact supporting members 25 and 29, contact plate 25, and outside wires 11 and 12, setting starting winding 14 in operation, until the load therein is reduced, core 19 is de-energized to release contact plate 25 from contacts 16 and 24, and the running winding 21 takes up the function of the running of the motor.

Whereas in the circuit shown in Fig. 1 wire 12 was connected to two terminals 33 in terminal plate 32, in the circuit illustrated in Fig. 9 said wire 12 connects with terminals 31 in terminal plate 30. While in the circuit shown in Fig. 1 line 23 connected with terminals 31 in the terminal plate 30, in Fig. 9 said line 23 connects with terminals 33 in terminal plate 32. In both circuits starting line 15 is connected to terminal 27 in plate 28, and contact 16.

The relay herein disclosed, adopted for use in connection with the alternating current motors, may be used in connection with a variety of circuits, as shown by two examples thereof illustrated in Figs. 1 and 9, and may be employed in connection with other electrical devices, using either a current coil or a potential coil. The relay herein disclosed is characterized by its compressed spring snap action due to springs 62 and 68 for compressing the armature.

While there is described herein a preferred embodiment of the present invention, it is nevertheless to be understood that minor changes may be made therein without departing from the spirit and scope of the invention as claimed.

What I claim as new is:

1. A relay of the class described comprising a base, a bracket mounted on said base, said bracket having an upright member, a foot at right angles to said upright member, said foot being mounted on said base, an arm having a free end and being at right angles to said upright member and on the opposite side of the upright member from the foot, and a downturned lip on the free end of said arm, an electromagnet mounted on said foot, an armature pivotally mounted in said upright member and extending transversely thereof with one end suspended above the electromagnet and the other below said arm, a pair of contacts mounted on said base, means actuated by said armature for bridging said contacts as said armature is attracted by the electromagnet on energization of the latter, a screw having a rounded end threadably mounted in the lip, a telescoping spring-biased plunger having arcuate

members on each end thereof, one of said arcuate members being pivotally mounted on the rounded end of said screw and the other member bearing against the armature, and a spring-pressed pin mounted in said arm adjacent the upright member, said pin resiliently bearing against said armature with increasing degree of compression as the armature is attracted to the electromagnet, the tension of said spring-biased plunger upon said armature decreasing as the armature is attracted by the electromagnet.

2. A relay comprising an electromagnet, a bracket, an armature mounted on said bracket, a pair of electrical contacts, means actuatable by said armature for bridging said contacts as said armature is attracted by said electromagnet, and a biased tensioning device pivotally mounted on said bracket, said tensioning device being in position to bear against said armature to cause the armature to swing away from the magnet when said magnet is deenergized and in position to bear substantially lengthwise of the armature when said magnet is energized.

3. A relay comprising an electromagnet, a bracket, an armature mounted on said bracket, a pair of electrical contacts, means actuatable by said armature for bridging said contacts as said armature is attracted by said electromagnet, a biased tensioning device pivotally mounted on said bracket, said tensioning device being in position to bear against said armature to cause the armature to swing away from the magnet when said magnet is deenergized and in position to

10

bear substantially lengthwise of the armature when said magnet is energized, and a second tensioning device mounted on said bracket, said second tensioning device being in position to bear against said armature under tension when said magnet is energized and to be free of the armature when the magnet is deenergized.
